Primary Examiner — David Muller*Assistant Examiner* — Nathan Johnston(74) *Attorney, Agent, or Firm* — Locke Lord LLP; Scott D. Wofsy(57) **CLAIM**

The ornamental design for a steerable guiding catheter handle, as shown and described.

DESCRIPTION

FIG. 1 is a perspective view of a steerable guiding catheter handle showing our new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The structural features depicted in broken lines have been shown for purposes of illustrating portions of the steerable guiding catheter handle that form no part of the claimed design.

1 Claim, 4 Drawing Sheets(56)
